UNITED STATES PATENT OFFICE.

ORLYSTIS M. POTTER, OF LARNED, KANSAS, ASSIGNOR TO MARK M. HENDERSON, OF NORWALK, CONNECTICUT.

COMBINATION-GARMENT.

1,144,240.

Specification of Letters Patent. Patented June 22, 1915.

Application filed December 9, 1912. Serial No. 735,736.

To all whom it may concern:

Be it known that I, ORLYSTIS M. POTTER, a citizen of the United States, residing at Larned, in the county of Pawnee and State of Kansas, have invented certain new and useful Improvements in Combination-Garments, of which the following is a specification.

My invention relates to combination garments and particularly to such garments for men's wear.

While the present improvements are more especially intended to be applied to the type of garment disclosed in my Patent No. 1,973,299, dated October 18, 1910, which comprises an outside or dress shirt and drawers, yet they may also be applied to a union undergarment.

In combination garments it is necessary that some provision should be made to allow the garment to accommodate itself to the movements of the wearer. In the ordinary union suit this result is accomplished by making the entire suit of elastic goods, such as flexible webbing. In a combined outer shirt and drawers, such as disclosed in my patent above mentioned, the garment is preferably made of woven fabric and provision is made for the various movements, as in stooping, by increasing the amount of cloth in the posterior portion across the seat and below the waist line, so that the shirt portion cannot work up and sag over the belt and trousers.

My present invention provides an improvement in the manner of accomplishing this result.

In garments of the closed-crotch type, it is desirable that the posterior portion should be so constructed that it will fit the anatomy of the wearer and normally remain closed, while at the same time permitting an opening of ample dimensions to be made. Among the difficulties heretofore experienced are the lack of such ample dimensions and the tendency of the flaps to sag and curl one below the other thereby causing the garment to remain normally open and also to be uncomfortable to the wearer. In my present invention, I am enabled to eliminate flaps, and yet to provide a convenient, comfortable garment.

In the drawings, Figures 1, 2 and 3 are

rear elevations of garments embodying my invention; Fig. 4, is a front elevation of the garment shown in Fig. 2; Fig. 5, is a pattern of one of the front pieces in a garment such as Fig. 3; Figs. 6 and 7 are rear and front elevations of a sleeping garment embodying my invention; Fig. 8, is a perspective view showing the manner of opening the nether garment; Figs. 9 and 10 are patterns of rear pieces of my garment showing the manner of providing a fullness in the seat portion; and Fig. 11, is a detail showing the manner of securing the seat fold at the side seams.

As previously stated, one of the purposes of my invention is to provide a fullness across the seat of the garment, below the waist line or top of the trousers, in order to accommodate the movements of the body, as in the stooping posture.

In Figs. 2, 3, 6 and 9, I have utilized the fold in the seat portion, as disclosed in my said prior patent. This is illustrated in Fig. 9 showing the left-hand side of the rear portion of the garment. The rear pieces are cut larger than the front portions by an amount indicated by the dotted line *d, e*, extension at the bottom of the leg. When the rear pieces are fitted to the front of the garment, the nether portion is shortened to the normal length by forming a fold *f, g*, across the seat portion and the fold is sewed into the side seam, as indicated in Fig. 11, to maintain its proper position.

In Figs. 1 and 10, I have disclosed another arrangement for securing the desired fullness across the seat by means of an excess of cloth upon each side of the nether garment portion, substantially wedge-shaped or triangular in outline, being widest at the center and tapering toward the sides where it disappears, so that there is no fold to be sewed into the side seams. The manner of forming this wedge-shaped fullness is illustrated in Fig. 10, which represents the left-hand portion of the rear of the garment. The cloth is first cut into the shape shown in full lines which causes the leg portion to be shifted outwardly to the left at an angle. In order to fit the rear pieces to the front of the garment so that the outside and inside edges coincide to be sewed into the side and leg seams, it is necessary to swing the leg por-

tion to the right about the point *h* until it occupies the normal dotted line position. This causes the triangular portion *h i k*, to pucker and form a fullness across the seat portion. It is obvious that the same result may be accomplished by first cutting said rear portion the normal shape shown in dotted lines and then cutting it across the line *h l*, and inserting a triangular piece *h i k*.
5 When the garment is completed, as shown in Fig. 1, the desired fullness is produced in the form of a double wedge, widest at the center and which provides the necessary cloth across the seat to allow for all of the
10 movements of the body, as in stooping, bending, etc., without pulling the nether portion above the trousers or waist-line to form a bulge above the trousers upon standing erect. There is no tendency, therefore, for the shirt
15 portion to work up and sag over the belt or top of the trousers.
20

When the rear of the garment is made of two pieces, as in Figs. 1 and 2, the rear pieces, shown in Fig. 9, are provided with an extension upon the inside of the leg, the part from *g* to *m*, passing under the crotch. When, however, the rear of the garment is cut from one piece, as illustrated in Fig. 8, the portion passing under the crotch forms an extension
30 upon the inside of the leg portion of the front pieces.

One of the main purposes of my invention is to provide a garment having a closed crotch and which will permit of being
35 opened so that one side of the nether portion may be drawn toward and across the center in the manner illustrated in Fig. 8. For this purpose I open the outer side of one leg portion from a point *p*, a little below the waist-line *n o*, to the bottom of the leg and fasten
40 the same with buttons *q* or other detachable retaining devices. I have found that it is sufficient to provide such an opening along the side only, as shown in Fig. 2. To make
45 the opening more ample and to facilitate ease of manipulation, the opening may be continued from the top point *p*, inwardly to a point *r*, which may be strengthened with a gusset. If desired the transverse cut or
50 opening may be carried to the center of the garment, but I prefer to extend it not more than half-way between the side and the center, as illustrated, because the remaining unbroken or continuous part of the leg and
55 seat furnish a firm support for the leg portion and will not require any buttons along the transverse cut or opening. In this manner, the cloth of the entire leg or a substantial portion thereof is a continuous integral
60 part of the combination garment from the neck to the bottom of the nether portion.

The fullness or fold across the seat assists in providing ample dimensions to enable the nether portion to be opened in the manner
65 described, and to be shifted from one side of

the garment across the median line of the seat as illustrated in Fig. 8, and I have found that a garment having either the form of fullness shown in Fig. 1 or that shown in Fig. 2, will coöperate with the single 70 straight side opening shown in Fig. 2, to provide proper facilities for opening the garment the desired amount.

My present invention enables the garment to be constructed with an unbroken integral 75 front part so that the garment will hang properly upon the body, having no transverse cut or opening to sag and no buttons or hooks to cause discomfort to the wearer. The pull from top to bottom is, therefore, 80 through a straight unbroken piece of fabric.

In Figs. 6 and 7, I have shown the same novel structural features as applied to a sleeping garment. A belt *s*, attached to one side at *t*, and passing through a loop *u* in the 85 back is adjustably secured at the other side, as by a series of button-holes *v*, adapted to engage a button *w*.

The combination shirt and nether garment may be made of any desired material. 90 The shirt may be of various styles, as dress or tuxedo style, plain or plaited bosom, or madras or other desirable material for negligée styles. As previously stated, this garment is also well adapted for underwear. 95

I claim:

1. In a union undergarment having a permanently closed crotch and a leg which is closed at its inner and outer sides, an opening originating in the back of the 100 undergarment and extending to the outside of the remaining leg thereof and then downwardly of said leg, thereby providing a seat flap.

2. A combination garment comprising in 105 a one piece suit, a shirt and nether garment or drawers, open in front from the neck to the crotch, and having an opening extending from a point below the waist along the outside of only one leg portion to the bottom 110 thereof and transversely from said point toward the center in the rear of the garment.

3. A union undergarment having a permanently closed crotch and an opening originating in its back and extending to the 115 outside of only one of the legs of said undergarment and downwardly of said leg, thereby providing a seat flap.

4. A union undergarment having a permanently closed crotch, an opening extending partially across the back of the undergarment and down the outside of one of its legs to the extreme lower edge thereof, thereby providing a seat flap of which the posterior portion of said leg constitutes a part, 120 and fastening means for said seat flap.

5. In a union undergarment having a permanently closed crotch and a leg which is closed at its inner and outer sides, an opening originating in the back of the under- 125

garment and extending to the outside of the remaining leg thereof and downwardly of said leg, thereby providing a seat flap.

6. A union undergarment having a permanently closed crotch, an opening extending partially across the back of the undergarment and then down the outside of one of its legs to the extreme lower edge thereof, thereby providing a seat flap of which

the posterior portion of said leg constitutes 10 a part, and fastening means for said seat flap.

In testimony whereof I affix my signature in presence of two witnesses.

ORLYSTIS M. POTTER.
